UNITED STATES PATENT OFFICE.

HARRY M. BURNELL AND MILLARD E. MOGG, OF CHICAGO, ILLINOIS

VALVE MECHANISM FOR FLUID-FUEL BURNERS.

SPECIFICATION forming part of Letters Patent No. 787,494, dated April 18, 1905.

Application filed October 10, 1904. Serial No. 227,913.

To all whom it may concern:

Be it known that we, HARRY M. BURNELL and MILLARD E. MÖGG, citizens of the United States, residing at Chicago, in the county of Cook and State of Illinois, have invented certain new and useful Improvements in Valve Mechanism for Fluid-Fuel Burners; and we do declare the following to be a full, clear, and exact description of the invention, such as will enable others skilled in the art to which it appertains to make and use the same.

This invention relates to improvements in automatic supply mechanisms for fluid-fuel burners, and more particularly to a thermostatically-controlled valve for regulating the supply of liquid or gaseous fuel to the burner of a steam-boiler or the like.

One object of the invention is to provide a simple and highly-efficient mechanism of this character which is especially adapted for use on steam-propelled motor-vehicles.

Another object of the invention is to provide a valve mechanism of this character which may be quickly and easily adjusted by hand to control the supply of fuel to the burner.

A further object of the invention is to improve and simplify the construction and operation of mechanisms of this character, and thereby render them more efficient and durable in use and less expensive to manufacture.

With the above and other objects in view the invention consists of certain novel features of construction, combination, and arrangement of parts, as will be more fully described, and particularly pointed out in the appended claims.

In the accompanying drawings, Figure 1 is a perspective view of a valve mechanism constructed in accordance with this invention. 40 Fig. 2 is a vertical sectional view through the same and a thermostat connected thereto. Fig. 3 is a vertical sectional view taken on the plane indicated by the line xx in Fig. 2. Fig. 4 is a horizontal sectional view taken on the plane 45 indicated by the line yy in Fig. 2. Fig. 5 is a detail perspective view of the valve, and Fig. 6 is a detail perspective view of the adjustable valve-seat.

Referring now more particularly to the 50 drawings, which disclose one practical embodiment.

ment of the invention, the numeral 1 denotes a casing or housing, preferably in the form of a casting, which comprises a hollow or tubular body 2, having adjacent to its upper end a laterally-projecting extension 3, which has its outer end flanged to provide a circular head 4. Said extension or projection 3 has an opening 5 extending therethrough and communicating with the bore 6 of the tubular body 2. In the bore 6 is formed an integral guide 7, in which a valve 8 is slidably mounted and concentrically disposed with respect to said bore. Said valve 8, as clearly shown in Fig. 5 of the drawings, consists of a cylindrical body portion 9, formed with a tapered or pointed lower end 10 and a cylindrical enlargement 11 at its upper end, which enlargement terminates in a reduced portion or valve-stem 12. This stem slides in an opening 13, formed in the lower end of a screw-plug 14, which closes the upper end of the tubular body portion 2 of the casing, provides a guide for the upper end of the valve, and serves as a stop to limit the opening or upward movement of the latter. In order to facilitate the feed of fluid fuel around the valve, the body portion 9 of the latter is formed with a series of longitudinally-disposed grooves or channels 15.

The valve 8 coacts with an adjustable valve-seat 16, formed in the upper end of a movable element 17, which closes the lower end of the tubular body portion 2 of the casing. The said element 17, as clearly shown in Fig. 6 of the drawings, is in the form of a screw-plug having its lower portion solid and cylindrical, as at 18, and its upper portion hollow or tubular, as at 19. The extreme upper end of the tubular portion 19 is externally screw-threaded, as at 20, with threads of a low pitch, which engage similar screw-threads 21, formed in a reduced portion 22 of the bore 6 of the tubular body 2 at a point below the opening 5 in the extension or housing 3. The extreme lower and outer end of the element 17 is formed with a polygonal head 23, by means of which the latter may be turned in the screw-threads 21 in order to adjust the valve-seat 16 toward or from the tapered lowered end 10 of the valve, which end projects into the bore or opening in the tubular portion of 100

the said element, as shown. That part of the tubular portion 19 of the element 17 immediately below the screw-threads 20 is of a reduced diameter, as shown at 24, so as to leave 5 a space 25 between it and the adjacent portion of the bore 6. The said portion 24 is formed with a series of radial openings or apertures 26, which permit the fluid passing below the valve to enter said space or chamber 25, as 10 presently explained.

In order to provide a fluid-tight connection or closure for the lower end of the bore 6, the latter is formed with an annular shoulder 27. Rings of suitable packing material 28 are 15 placed upon the portion 18 of said element 17 and confined between said shoulder and the inner end of a screw nut or plug 29, through which said portion 18 projects. By screwing said nut into the internally-screw-threaded 20 lower end of the tubular body 2 the packing 28 may be jammed tightly around the element 17 to prevent the escape of oil or gas.

The oil, gas, or fluid fuel is admitted into the casing through a connection 30 in the form 25 of an externally-screw-threaded nipple, which projects laterally from one side of the casing and opens into the bore 6 above the valve. After passing through said valve the oil or gas passes into the space or chamber 25, as 30 previously stated, and then passes out of a nipple or outlet connection 31, similar to the nipple 30. These inlet and outlet nipples are suitably connected, the former to a source of supply and the latter to the main burner of 35 the furnace or heater. In order to conduct the oil or gas to the pilot-light, usually, if not always, used on burners for steam-carriages and the like, a third nipple or outlet connection 33 is provided intermediate the other 40 two, so that it opens above the valve and is therefore not controlled by the latter, it being necessary to have the pilot-light always burning.

The valve is automatically controlled by 45 means of a thermostat, as illustrated in Fig. 2 of the drawings. Any form of thermostat may be used; but, as shown, it comprises a tube 34, of copper or other suitable material, inclosed in a tubular casing 35, having suitable steam connections 36 with a steam-boiler and screwed upon the outer end of a nipple or boss 37, in which the tube 34 is secured. Said nipple 37 is formed upon a circular disk or cover-plate, which is bolted, as shown at 50 38, upon the head or flange 4 of the casing in order to close the outer end of the opening 5 in the latter, a washer or packing-ring 39 being interposed between said plate and head to effect a fluid-tight connection.

55 Mounted in the tube 34 is a rod 40, of steel or other metal, which has its inner end projecting through an opening formed in said cover-plate. Said inner end of the rod 40 contacts with the short arm 41 of a bell-crank lever 42, which is fulcrumed at 43 between two

arms of a bracket 44, secured by screws 45 upon the inner face of said cover-plate. The long arm 46 of said bell-crank is forked or bifurcated, as at 47, to engage the enlarged portion 11 of the valve. The parts will be so proportioned and adjusted that when the boiler temperature exceeds the required degree the excessive heat will cause the tube 34 to expand to such an extent as to enable the valve to close by its own weight and that of the 75 long arm of the bell-crank lever 42, it being understood that the rod 40 will move longitudinally in the required direction to cause the valve to close when the said tube 34 is thus expanded. As the valve closes in the 80 valve-seat 16 it cuts off the supply of fuel to the main burner. When the boiler temperature becomes less than the required degree, the tube 34 contracts to a corresponding extent and moves the rod 40 in the required direction to open the valve 8 from its seat, so as to cause an increased quantity of fuel to be supplied to the main burner. Hence the supply of fuel to the main burner is automatically controlled, with the result that the 85 pressure of the steam is prevented from varying excepting to a very slight extent.

The valve preferably closes by gravity, as shown, and its opening may be readily regulated by adjusting the valve-seat 16, as previously stated. 95

From the foregoing description, taken in connection with the accompanying drawings, the construction and operation of the invention will be readily understood without requiring a more extended explanation. 100

While the preferred embodiment of the invention is here shown and described, it will be understood that we do not wish to be limited to the precise construction herein set 105 forth, since various changes in the shape, proportions, and minor details of construction may be resorted to without departing from the principle or sacrificing any of the advantages of our invention. 110

Having thus described our invention, what we claim as new, and desire to secure by Letters Patent, is—

1. A mechanism of the class described, comprising a casing having inlet and outlet openings, a valve-seat opening between the inlet and outlet openings, an adjustable valve-seat in said valve-seat opening, an opening opposite said valve-seat opening and a guide device between the valve-seat opening and the opening 115 which is opposite the same, a longitudinally-movable valve in said casing, guided in said guide device and extending into said valve-seat opening, an adjustable valve-seat for said valve in said valve-seat opening and having a stem projecting out of said casing and serving as a means whereby said valve-seat may be adjusted, an adjustable stop device for the valve in the opening which is opposite the valve-seat opening, a bell-crank in said cas- 120 125 130

ing connected to said valve, and a thermostat to control said bell-crank and operate said valve.

2. A mechanism of the character described comprising a casing having inlet and outlet openings, internal screw-threads intermediate said openings, an integral guide above said screw-threads and an internal shoulder below the latter, a tubular element adjustably engaged with said screw-threads and formed with a valve-seat at its inner end and a series of apertures below said seat to afford communication between said tubular element and the interior of said casing below said screw-threads, 5 a packing for the outer end of said element engaged with said internal shoulder, a packing-nut for said packing, and a valve slidably mounted in said guide and coacting with said valve-seat, substantially as described.
- 20 3. A mechanism of the character described comprising a casing consisting of a tubular portion having a hollow lateral extension or housing, inlet and outlet connections for the said casing, internal screw-threads in said casing intermediate said connections, an integral apertured guide in said casing above said

screw-threads, an annular shoulder in said casing below said screw-threads, a tubular element adjustably engaged with said screw-threads and formed with a valve-seat at its inner end and a series of apertures adjacent to said seat to afford communication between said tubular element and the interior of said casing below said screw-threads, a packing surrounding said element and engaged with said 30 annular shoulder in said casing, a packing-nut for said packing, a valve slidably mounted in said guide and coacting with said valve-seat, a cover-plate upon the outer end of said extension or housing, a bracket secured upon 35 said cover-plate, a bell-crank pivotally mounted in said bracket and engaging said valve, and a rod for operating said bell-crank, substantially as described.

In testimony whereof we have hereunto set 45 our hands in presence of two subscribing witnesses.

HARRY M. BURNELL.
MILLARD E. MOGG.
